Attorney.

UNITED STATES PATENT OFFICE

HEINRICH LESCHHORN, OF ZUFFENHAUSEN, NEAR STUTTGART, GERMANY

FORM OF THE KIND USED IN OFFICE WORK

Application filed May 1, 1931, Serial No. 534,355, and in Germany May 20, 1930.

The present invention relates to a novel combination of forms of the kind used in office work, such as invoices, advices of receipt, despatch notices, pay rolls and the like, and effects a considerable saving in time and material by simplifying the actual writing work. The application of the invention will be found particularly profitable in connection with work that has to be regularly done at 10 stated periods, such as, for example, pay roll work.

Forms that are superimposed or telescoped like scales to facilitate writing work are known already. They serve the purpose to 15 save space by covering the lettering at the head of the various strips of which they consist so that the lines of the undivided superposed forms may be moved more closely together. In this way the general arrangement 20 of accounts or the like becomes clearer. However, forms of this kind are expensive to produce and therefore uneconomical. Furthermore, they do not permit of perfect register and can hardly be inserted in typewriters, 25 as their inequalities render motion within the machine quite difficult; their raised scalloped portions stick in the machine and cause warping and distortion. Owing to unequal pressure on the projecting margins of the strips, 30 these forms are liable to get soiled very easily.

The invention eliminates these defects almost completely without giving up the advantages connected with partially covered 35 superimposed or telescoped forms.

The combination of forms according to the invention comprises two or several transversely slotted sheets which are not superposed like scales but secured by being placed 40 perfectly flat and level upon one another. These sheets are held together by means of gummed adhesive strips in such a way that the slots are staggered relative to one another for the width of an adhesive strip. 45 In this way, in the total form, one strip of an upper sheet always constitutes a form together with a strip of the underlying sheet or more than two sheets may be united and each form consist of three or more strips. If 50 a covering sheet without slots is then placed

on either side of the combined sheets and preferably pasted down at the margins, the entire combination may be passed through a typewriter without causing the sheets to stick in the machine or become displaced relative to one another. The cost of producing such form combinations is quite low which are therefore economical and adapted for widest use. 55

One form of the invention is illustrated in 60 the accompanying drawing, in which Figure 1 is an elevation of a form combination composed of two superposed sheets; and Fig. 2, a section thereof.

Referring to the drawing, two or more 65 sheets *q* and *r* provided with the longitudinal slots *s* and *t* are placed upon one another and interconnected by a binding agent, such as the gummed adhesive strips *u*, so that the slots are staggered relative to one another 70 by the width of an adhesive strip. The lower sheet or sheets carry preferably the heading of the form concerned. When the lateral holding strips are separated along the line *g*, the sheet combination will be divided into 75 individual forms, each of which consists, for example, of a strip of the sheet *q* and a strip of the sheet *r*. On one or both sides of the combination a covering sheet *p* may be provided. 80

I claim:—

1. A combination form comprising a plurality of superposed sheets transversely slotted to provide strips, and adhesive strips for holding together the said sheets, the slots of 85 the said sheets being staggered relative to one another by the width of an adhesive strip and each strip of a sheet being adhesively connected with a strip of the underlying sheet.

2. In a combination form according to 90 claim 1 sheets without slots connected with the margins of the slotted sheets.

In testimony whereof I affix my signature.

HEINRICH LESCHHORN.
